UNITED STATES PATENT OFFICE.

WILLIAM O. KENNINGTON, OF LONDON, ENGLAND.

VACUUM-OPERATED BRAKE.

Application filed November 5, 1924. Serial No. 747,917.

REISSUED

To all whom it may concern:

Be it known that I, WILLIAM OSCAR KENNINGTON, a British subject, residing at The Hyde, Hendon, London, N. W. 9, England, have invented a new and useful Improved Vacuum-Operated Brake, of which the following is a specification.

This invention has reference to vacuum operated brakes for automobiles and like vehicles and is more particularly but not exclusively concerned with vehicles of this type wherein a brake is provided for each wheel.

The primary object of my invention is to provide an improved braking system for automobiles and like vehicles consisting of few parts and capable of being economically constructed easily operated and at the same time being highly efficient in use.

With these ends in view and such others as may hereinafter appear or are incidental thereto the invention in its broadest aspect may be said to consist in the provision of means whereby the suction of the engine is utilized to actuate the brake mechanism when the throttle valve of the engine is moved beyond what is normally the closed position.

More specifically regarded the invention is embodied in an arrangement wherein the suction of the engine actuates a piston bellows or other appropriate pressure contrivance when the throttle valve has been moved to a position beyond what may be termed the normally closed position of the valve said piston or like contrivance being then adapted to actuate the mechanism whereby the brakes are applied.

In accordance with my invention I provide that part of the intake pipe of the engine with a recess so located that when the throttle valve is in a position to restrict or interrupt the supply of combustible mixture from the carburettor to the engine or in other words when it is in the normally closed position the upper lip of the recess is opposite the edge of the throttle valve. The aforesaid recess communicates by means of a suitable connection such as a pipe with a suction operated device for example a piston or bellows or other like contrivance adapted in operation to actuate the brake mechanism through suitable connections when the aforesaid suction device is subjected to the suction of the engine as will presently be explained.

The throttle valve which may be of the ordinary butterfly piston or other convenient type is mounted in the intake pipe of the engine and when fully opened permits the passage of the maximum quantity of combustible mixture and when it is desired to decelerate the engine the throttle is moved into the requisite position and when it is in

what is normally the closed position it restricts or prevents the passage of combustible mixture to the engine all as is usual in internal combustion engines of the type to which this invention refers. According to this invention in this position the throttle

is at one edge of the aforesaid recess in the intake pipe and if it is now desired to apply the brakes the throttle is moved across the recess towards the other edge and thereby places the piston or bellows or other pressure mechanism in communication with the suction side of the throttle valve whereby the said pressure mechanism is gradually subjected to the suction of the engine and

the brakes which as above stated are connected to the pressure mechanism are applied. When the throttle is in the position just described the pressure mechanism is subjected to the full suction effect of the engine and during the movement of the throttle from the normally closed position to the extreme position the combustible mixture can leak past the recess around the edge of the throttle valve to the engine whereby the latter is supplied with sufficient mixture to enable it to turn over and at the same time the brakes are gradually applied.

In order that the invention may be clearly understood by those skilled in the art to which it appertains reference will now be made to the accompanying drawings which illustrate one manner of carrying the invention into effect.

Fig. 1 represents a section through the intake pipe of an internal combustion engine and of one form of pressure mechanism for operating the brakes in accordance with my invention and

Fig. 2 is a diagrammatic view in sectional elevation of the general arrangement of parts wherein my invention is embodied.

In the drawings wherein the same reference numerals indicate the same or similar parts 1 represents the intake pipe of an internal combustion engine for use in an automobile or the like and having a throttle

- valve 2 for controlling the passage of combustible mixture to the engine the intake being provided with a recess 3. Communicating with the recess 3 by means of a pipe 5 4 is a pressure operated device comprising a cylinder 5 having a piston 6 to which is secured a brake control rod 7 adapted to be secured to the brake mechanism whereby the brakes are applied to the wheels.
- 10 In the construction illustrated I have shown a spring 8 for the purpose of assisting in returning the rod 7 when the suction of the engine on the piston 6 is released to the inoperative position thereby bringing the brake mechanism to the "off" position.
- 15 The rear side of the piston 6 may be open to atmosphere but should serious leakage of air past the piston occur it might conceivably detrimentally affect the composition of the combustible mixture when the parts are in position to apply the brakes. I may therefore provide a pipe connection 9 between the intake pipe 1 on the carburettor side of the throttle valve 2 and the rear of the piston 6 so that any leakage past the latter will be leakage of normally rich mixture.
- 20 In operation when it is desired to decelerate the throttle is moved into the normally closed position shown in Fig. 1 in which position it restricts or prevents the passage of combustible mixture to the engine. If now it is desired to apply the brakes the throttle is moved across the recess 3 whereby a 25 piston 6 is gradually subjected to the engine suction and the brakes applied. During this movement of the throttle the combustible mixture can leak around the edge of the throttle to the engine whereby a sufficient quantity of mixture is supplied to the engine to enable it to run or turn over and the brakes gradually applied. The means whereby this is effected is more 30 clearly shown in Figure 2 the movement of the throttle 2 being controlled by a pedal 10 mounted on a spindle 11 and having an extension 12 connected by means of a rod 13 to the usual arm 14 of the throttle valve spindle 15. When it is desired to de-celerate 35 pressure on the pedal 10 is decreased whereupon a relatively strong spring 16 moves the throttle into the desired position. If now it is desired to apply the brakes the pressure on the pedal 10 is still further decreased 40 and the spring 16 moves the throttle beyond the normally closed position. During this movement a clutch member 17 on the extension 12 engages a co-operating clutch member 18 on an arm 19 mounted on spindle 11 45 and moves said arm 19 against the action of a relatively weak spring 20 which normally retains the arm 19 in contact with a stop 21. Immediately the spring 16 begins 50 to move the pedal 10 upwards against the action of the spring 20 the driver of the

70 vehicle feels a difference in the pressure requisite for operation of the pedal 10 and is advised thereby of the position of the throttle and that the brakes are being applied.

75 Any other convenient indicating means may be employed and if desired a stop may be provided to arrest the pedal lever or the like actuating the throttle valve when this latter has been moved to the normally closed position means such as a lever or the like or a control on the steering wheel being provided to move the stop out of the path of the pedal or lever operating the throttle to permit said lever and consequently the 80 brakes applied.

85 It will be understood that I may if desired provide means for co-ordinating my improved brake mechanism with the ordinary foot or hand brake in such a manner that a preliminary braking may be effected by the means I have described followed by further braking by means of the foot or hand brake. Means may also be provided 90 for actuating the rod 7 by manually or pedal controlled means but as these refinements will be apparent to those skilled in the art to which this invention appertains 95 further description thereof is here deemed unnecessary.

100 While I have described one construction of parts of my improved brake mechanism and the operation thereof I am aware that changes of construction and operation may be made without departing from the spirit and scope of the invention for example instead of one pressure device as shown and described I may provide more than one as may be deemed advisable according to the 105 kind of vehicle to which my invention is to be applied and I therefore do not wish to be understood as limiting the scope of my claims by the positive terms employed in connection with the description.

110 What I claim is:

1. A vacuum operated brake mechanism for automobiles and like vehicles, comprising, the combination of the usual brake and throttle mechanism, and means operated by the suction of the engines to actuate the brake mechanism when the throttle is moved beyond what is normally the closed position.

2. A vacuum operated brake mechanism for automobiles and like vehicles comprising a pressure operated device adapted to be actuated by the suction of the engine when the throttle valve of the engine is moved beyond the normally closed position and mechanism connecting said device to the brakes of the vehicle.

3. A vacuum operated brake mechanism for automobiles and like vehicles comprising a pressure operated device means for

- connecting said device to the brakes of the vehicle and means for moving the throttle valve of the engine beyond the normally closed position to permit the suction of the engine to actuate the pressure operated device and apply the brakes.
4. A vacuum operated brake mechanism for automobiles and like vehicles comprising a pressure operated device mechanism operating therewith to apply the brakes to the wheels of the vehicle when the said device is actuated means whereby the throttle valve of the engine can be moved beyond the normally closed position to permit the suction of the engine to actuate the pressure operated device and means whereby the engine is kept running when the throttle valve has been moved beyond the normally closed position.
5. A vacuum operated brake mechanism for automobiles and like vehicles comprising a pressure operated device mechanism for connecting said device to the brakes of the vehicle means whereby the throttle valve of the engine can be moved beyond the normally closed position means for establishing communication between the suction of the engine and said device when the throttle valve is moved beyond the normally closed position so as to actuate said device and apply the brakes means whereby combustible mixture can leak past the throttle valve to supply the engine with fuel when the throttle valve has been moved beyond the normally closed position and means for returning the brake mechanism to the "off" position when the throttle valve is opened or partially opened.
- 6: A vacuum operated brake mechanism for automobiles and like vehicles comprising a pressure operated device mechanism for connecting said device to the brakes of the vehicle means whereby the throttle valve of the engine can be moved beyond the normally closed position means whereby when the throttle valve is moved beyond the normally closed position communication is established between the suction of the engine and said device so as to actuate said device and apply the brakes means whereby combustible mixture can leak past the throttle valve to supply the engine with fuel when the throttle valve has been moved beyond the normally closed position and means for indicating the position of the throttle prior to the brakes being applied.

W. O. KENNINGTON.
